METHOD OF AND APPARATUS FOR HANDLING STRANDS

Leo L. Weaver, Cranford, N. J., assignor to Western Electric Company, Incorporated, New York, N. Y., a corporation of New York

Application December 27, 1933, Serial No. 704,099

8 Claims. (Cl. 96—3)

This invention relates to a method of and apparatus for handling strands and more particularly to a method of and machines for serving and braiding.

5 An object of the invention is to provide a method of and apparatus for putting cover strands on cores by imposing rotation upon a restricted portion only of a continuously advancing torsionally substantially rigid core and applying 10 a cover strand to the rotating part of the core, the characteristic feature of the apparatus to produce this effect being a duplex rotary flier having two spaced opposed operative arms defining a single path through the flier for the core, 15 and a purpose being to enable the use of stationary cover strand supplies and stationary supports therefor.

With this and other objects in view, one embodiment of the invention contemplates a serving 20 or braiding machine or the like, in which the strand supplies may rotate on their individual axes but are not displaced as a whole, being stationary in location within a revolving flier. The flier is duplex and the serving or braiding is 25 done at a point in the axis of revolution of the flier between the two parts of the flier in such a way that the core strand enters the flier and the served or braid covered core leaves the flier devoid of rotation while rotating on itself at the 30 point of serving or braiding.

Other objects and characteristics of the invention will appear from the following detailed description of embodiments thereof in a serving machine and in braiding machines adapted to 35 apply the method, taken in connection with the accompanying drawings in which the same reference numerals are applied to homologous parts in the several figures and in which

Fig. 1 is a diagrammatic view in elevation and 40 partly in vertical section of a serving machine embodying the invention;

Fig. 2 is a detached diagrammatic view in plan of the supply assembly as disposed in Fig. 1;

Fig. 3 is a similar view of another form of supply assembly;

Fig. 4 is a similar view in side elevation of a third form of supply assembly;

Fig. 5 is a diagrammatic view in elevation and partly in vertical section of a braiding machine 50 embodying the invention;

Fig. 6 is a sectional plan view of the braiding head proper taken on the line 6—6 of Fig. 5;

Fig. 7 is a broken view thereof in internal radial elevation;

Fig. 15 is a view similar to Fig. 1 showing a modified form of serving machine embodying the invention;

Fig. 16 is a detached view from the side of two of the canted outer sheaves on line 16—16 of Fig. 15, and

Fig. 17 is a similar top view on the line 17—17 of Fig. 15.

In the machine disclosed in Figs. 1, 2, 3 and 4, a framework 30 has mounted therein a flier generally indicated by the numeral 31 and having exit and entrance arms 32 and 33 respectively. The strand exit ends of both arms of the flier are supported in and drive a stub shaft 34 journalled in the frame in any approved manner.

The strand entrance ends of the two arms of the flier are supported in and driven by a stub shaft 35 also journalled in the frame in axial alignment with the shaft 34. The arm 33 at its lower end opens in the axis of the shaft 35 at the bottom end thereof and at its upper end the arm 33 opens out axially from the bottom end of the shaft 34. Similarly the lower and upper ends of the arm 32 open out respectively from the centers of the upper ends of shafts 35 and 34.

A supply support 36 is journalled on the upper end of the shaft 35 and carries means including strand guides 55 to support a plurality of supply cops 37 with freedom to rotate on their own axes.

Shaft 35 is provided at its lower extremity with a spur gear 38. Above its bearing the frame is formed with a spur gear 39. Gear 39 meshes with a planetary gear 40 mounted on the lower end of a shaft 41 journalled in a bracket on the shaft 35 and having at its upper end a second planetary gear 42. Gear 42 in turn meshes with a spur gear 43 carried by the supply support 36. Gear 38 meshes with and is driven by a gear 44 mounted on a shaft 45 journalled in the frame 30. Shaft 45 in turn is driven from a power shaft 46 through

10

15

20

55

bevel gears 47 and 48. Shaft 46 is driven from any convenient power source not shown, and drives a take-up reel 49 through an appropriate belt 50 and pulleys 51 and 52.

5 A core supply reel 53 is mounted below the bottom ends of the shaft 35 and flier arm 33. A capstan 54 is provided to assist the take-up reel in pulling the strand through the apparatus.

10 The core 56 is a wire or other strand analogous to a wire in being torsionally substantially rigid so that it does not accept any twist or torsional deformation to any substantial extent in its progress through the apparatus.

15 When the machine is in operation the flier 31 is driven by the gears 44 and 38 and the shaft 35, but the strand supply support 36 is held stationary by the gears 39, 40, 42 and 43. Assume that the flier is rotating clockwise as looked at from above. The core 56 enters the lower end 20 of the arm 33 upwardly with no motion except its longitudinal advance, and emerges downwardly from the upper end of the arm 33 rotating on its own axis in the same sense as and at twice the speed of the flier. Between its exit from the 25 upper end of arm 33 and its entrance into the lower end of arm 32, the core is engaged by one or more cover strands 57 drawn from the supply cops 37 through the guides 55. Since the core is rotating relatively to the cops which are stationary in location, the strands 57 are served on the core 56 at the rate of two turns each for each revolution of the flier.

30 The covered core still rotating at twice the speed of the flier enters the lower end of the arm 32; but since its passage through the arm 32 is opposite in sense to its passage through the arm 33, the finished covered strand emerges from the upper end of the arm 32 with its rotation annulled and is wound on the take-up reel 49.

35 40 Thus in this machine the strand at the serving point is rotated while the serving supply head is held stationary. Hence it is not necessary to form the supply head with extreme or in fact with any attention to symmetry and centrifugal balance, either static or dynamic. Hence if a single strand is to be served it may, if desired, be drawn from a coiled supply 58 surrounding the core as is customary for balance in some prior machines, as shown in Fig. 3, but may also advantageously be drawn from a completely unsymmetrically located supply reel or cop 59 supported on an unsymmetrical support as shown in Fig. 4.

45 50 In the embodiments disclosed in Figs. 5 through 55 11, the mechanism of Fig. 1 is repeated in inverted position in the upper half of Fig. 5. The core 56 drawn from the supply reel 53 enters the upper end of the flier arm 33 at the top of the machine without rotation and emerges therefrom at the lower end of arm 33 rotating in the same sense as the flier which here rotates counterclockwise, but at twice its speed. The core receives a serving of cover strands drawn from the stationarily supported cops 37 and enters the upper end of the arm 32 still rotating. The served core emerges from the lower end of arm 32 without rotation and passes one or more times around an auxiliary capstan 60, driven in any convenient fashion not shown. This capstan acts merely as a booster to assist in lessening the load on the final take-up reel 49.

55 60 The served core then enters a second duplex flier 131 similar in all essentials to the one just described and rotating at the same speed but in the opposite direction. Here, however, there is

an additional mechanism mounted within the flier. This comprises a roughly saucer-like rotatable frame 162, journaled on the adjacent end of the shaft 134 and with its upturned and inturned rim surrounding a group of stationary 5 strands supply cops 137. A plurality of sheaves 163 equal in number to the served strands 57 is mounted in the frame 162 adjacent the exit end of the arm 133. A spring pressed tensioning sheave 164 is mounted radially adjacent to each 10 sheave 163, and an outer guide sheave 165 is mounted on the outside of the upturned rim of the frame 162 in radial alignment with each pair of sheaves 163 and 164. A perforation in the rim leads from each sheave 165 to a group of switching mechanisms 166 carried within the rim of the frame 162.

15 A train of gearing 167, 168—174, 175, whose operation is clearly evident from the drawings and which in detail is not pertinent to the present invention, drives the frame 162 in the same direction as and at four times the speed of the flier 131.

20 As the core 56 leaves the lower end of the flier arm 133 the strands 57 served thereon in the 25 flier 31, are stripped off the core and led over the several sets of sheaves 163, 164 and 165 to the switching mechanisms 166, and thence back to the core 57 just before the latter enters the upper end of the flier arm 132.

25 30 The strands 157 from the group of supplies 137 are brought directly to the core at the same time as the strands 57.

35 The served core enters the flier arm 133 without rotation and leaves the flier arm rotating 35 on its own axis in the same direction as the flier, i. e. clockwise, but at twice its speed. Since the frame 162 and therewith the sheaves 163 rotate at four times the speed of the speed of the flier, the sheaves rotate around the core at twice the 40 speed of the core and so are enabled to unlaid and take off the strands 57 evenly from the core.

45 At the braiding point just before the core enters the upper end of the flier arm 132, the core is still rotating at twice the speed of the flier, 45 the strands 157 are not revolving and the re-applied strands 57 are revolving around the core at twice the speed of the latter. Hence if it were not for the switching mechanisms 166, the two sets of strands 57 and 157 would be laid or served 50 on the core in two oppositely spiraled layers. The function of the mechanisms 166 is to guide the strands 57 alternately above and below the strands 157 so that the resultant interweaving of the strands forms a braided cover on the core. 55

55 The covered core still rotating then enters the arm 132 at its upper end, leaves the flier at the bottom thereof without rotation, and is coiled on the take-up device 49.

60 Evidently if the operation is to begin with a core already covered with a wound serving, the portion of the mechanism comprising the flier 32 may be omitted and the served core introduced directly from a supply thereof into the flier 132. Thus an apparatus may be arranged to convert 65 a served covering into a braided sheath.

65 70 Figs. 6, 7 and 8 disclose on an enlarged scale the braider head and in particular the details of the strand switching mechanism 166. This device as disclosed is set up to handle four strands 70 in each direction but has room to be arranged to handle up to eight. As disclosed, a spider-like support 136 having depending arms 138 is journaled on the shaft 135 and held against rotation by the gears 139, 140, 142 and 143. On each of 75

the depending arms 138 is rotatably mounted on a radial axis an appropriately beveled spacing roll 176 and between each alternate pair of spacing rolls floats one of the switching devices proper.

5 A switching device proper comprises as framework an outer slightly dished circular disc 177 and an inner flat oval contoured disc 178. Three equi-spaced shafts 179, 180 and 181 are rigidly mounted in the two discs and join them together 10 rigidly since the three shafts are not parallel but are nearer together in the disc 178 than in the disc 177. A roller 182 comprising four completely encircling, spaced radial flanges is rotatably mounted on the shaft 179 and rolls with two of its 15 flanges 185 and 187 on a slightly inclined trackway 189 on the floor of the saucer-like frame 162. The flange 186 is provided peripherally with gear teeth which mesh with a corresponding circular rack 190 formed on the frame 162. The outermost flange 188 is a trifle greater in diameter than the other three and extends into a corresponding groove 191 in the floor of the frame 162 which prevents any outward movement of the whole assembly in the frame 162 while inward movement 20 is prevented by the slant of the trackway 189.

Each of the shafts 180 and 181 carries a similar four flanged roller which engages a similar trackway and rack formed on the under side of the in-turned rim of the frame 162. The four flanges 30 of each roller are formed with slots in generally radial but preferably slightly spiral alignment to pick up, receive and guide the strands 57 in predetermined alternation up and down to pass alternately above and below the strands 157.

35 The spacing rolls 176 confine the switching roll assemblies laterally, and the latter are confined vertically by the trackways and radially by the grooves 191.

The strand 57 enters the frame 162 at its mid 40 height passing, if undeflected, just below the spacing rolls 176 and impinging on the advancing switching mechanism a little below the lateral apex of the elongated disc 178. The strand actually strikes first against the flanges of the roller carried by the shaft 181 and slides downwardly. If not picked up by the slots of these flanges it is 45 picked up by the slots of the flanges on the bottom roller on shaft 179 and is carried down under the switching mechanism and released. If 50 picked up by the roller on the shaft 181, the strand is carried up over the switching device, delivered to and caught up by the slots of the roller on shaft 180, carried on over and released. The timing of the slots in the roller on shaft 181 55 determines whether the strand 57 at a given encounter is carried up over or down under a corresponding strand 157. By appropriate timing, number and disposition of the slots the braid may be given its desired character, one over one under, two over two under, etc.

A stub shaft 192 rigidly mounted in the center of each of the discs 178 extends radially inwardly therefrom. These shafts serve to support the supply cops 137 from which the strands 157 are 60 drawn through appropriate guides 155 mounted on the discs 178. The guides 155 are of spring material and press against the circular bases 200 of the cops to act as friction brakes.

65 Additional switching devices and supply cops may be installed if desired as shown in dotted lines in Figs. 6 and 7.

An alternative arrangement of the braider head is disclosed in Figs. 9, 10 and 11 in which the 70 supply cops 137 are positioned radially exterior

to the switching devices, an arrangement which enables the use of larger supply cops.

In Figs. 12, 13 and 14 the invention is shown embodied in another form of braiding machine in which the same principles are used.

This machine is mounted in a framework 30 and comprises near the bottom a flier having only one operative arm 210, the other arm being merely a balancing dummy. A supply support 236 is mounted as before to be stationary within the flier and carries supply cops 37 from which cover strands 57 are drawn through guides 55. The strands emerge from the top of the flier in a twistless, rotating bundle and pass upwardly through both arms of a second flier 231 rotating 15 in the same direction and at twice the speed of the flier 210. A third flier 211 rotates within the flier 231 in the same direction and at one-fourth the speed of flier 231, and a core supply reel 53 is supported in a non-rotating frame 212 within 20 the flier 211.

A core strand 56 is drawn from the reel 53 and passes through one arm of the flier 211, the other arm being merely a balancing dummy. The core 56 emerges from the top of the flier 211 rotating 25 in the same direction and at half the speed of rotation of the bundle of cover strands 57 which surround the core but are not wound thereon. The associated core 56 and strands 57 then enter a braiding head 262 constructed like the head 162 30 of Figs. 6, 7 and 8 or of Figs. 9, 10 and 11, which rotates in the same direction and at the same speed as the flier 231. In this head 262 a second set of cover strands is applied to the core at the same time that the strands 57 are applied there- 35 to in the fashion previously disclosed in the description of head 162, so that the core emerges from the braider head with the two sets of cover strands braided thereon. The covered core is now rotating at half the speed of the flier 231. 40

A capstan 260 receives the covered core from the braider head and is mounted as shown to revolve in the same direction and at the same speed as the cable rotates as well as to rotate in step with the longitudinal progress of the cable. 45

On leaving the capstan the cable enters a fourth flier 213 rotating in the same direction and at half the speed of the cable. The cable emerges downwardly from the top of this flier, in a direction opposite to its progression up to this 50 point. Hence this flier annuls the rotation of the cable, which is finally coiled on the stationarily mounted take-up reel 49.

The general driving mechanism is obvious from the drawings and from the previous disclosures 55 and so it is not necessary to describe it here in detail, but three of the special driving mechanisms are thought to be novel, namely the drive for the double flier and core supply support 211, 231, 212, the support and drive for the capstan 60 260, and the drive for the take-up reel 49.

As shown in Figs. 12 and 13, the lower end of the flier 231 is supported in a shaft 234 journaled in the frame 30. The lower end of the flier 211 is itself a stub shaft supported by a thrust bearing on the upper end of the shaft 234 and in turn supporting a thrust bearing which carries the lower end of the supply reel frame 212. Similarly the upper end of the flier 231 is carried by a shaft 235 journaled in the frame 30 and supporting a bearing for the upper end of the flier 211 which in turn carries a bearing for the upper end of the frame 212.

A bevel ring gear 214 is rigidly mounted on the flier 231 and is driven by a bevel gear on a shaft 75

driven from the main drive shaft 46. This drives the flier 231. A wobble ring gear 215 is rotatably mounted on the flier 231 and meshes on one face with a stationary gear 216 on the frame 30 and on 5 the other face with a bevel ring gear 217 rigid on the flier 211 thus driving the flier 211. A gear 218 rigid on the shaft 235 meshes with a gear 219 rigidly mounted on a planetary shaft 220 journalled in the upper end of the flier 211. A gear 10 221 also rigidly mounted on the shaft 220 meshes with a gear 222 rigid on the head of the frame 212. The gear train from 218 to 222 is so proportioned and arranged that the frame 212 is held stationary with respect to the frame 30.

15 As shown in Figs. 12 and 14, the capstan 260 is revolvably mounted on a horizontal axis in a frame 223 rotatably supported at its upper end in the frame 30 by any suitable means not shown. The lower end of the frame 223 is supported by 20 a thrust bearing carried by the frame 30. A ring gear 224 rigidly mounted on the outside of the frame 223 is driven as shown in Fig. 12 from the main drive shaft 46 and thus serves to rotate the frame 223 and therewith the capstan 260 about a 25 vertical axis. A gear 225 is rotatably mounted on a radial shaft carried by the frame 223 and meshes with a stationary gear 226 on the frame 30 being driven thereby as the frame 223 rotates. The gear 225 also meshes with an appropriate gear sequence 227, 228 to revolve the capstan 30 260 about its horizontal axis.

As shown in Fig. 12, the flier 213 carries a ring gear 229 which meshes with a corresponding gear 209 rigidly mounted on a shaft 208 journalled 35 in the frame of the take-up reel 49. The shaft 208 in turn drives the take-up reel through the pulley 50, belt 51 and pulley 52. The flier 213 is driven and the reel frame 207 is held stationary by any approved means such as already described.

40 In Figs. 15, 16 and 17 there is disclosed a modified form of the serving machine shown in Figs. 1, 2, 3 and 4, in which the flier is replaced by a system of canted guide sheaves.

In this embodiment, the flier arms 32 and 33 45 of Fig. 1 are replaced by a pair of pluralities of guide sheaves 332, 432 and 333, 433 respectively. An inner sheave 333 is mounted in the shaft 35 to receive a core strand 56 moving axially up through the shaft 35 and pass it on to an outer 50 sheave 333 mounted on the outer extremity of a rigid arm 310 extending substantially radially from the shaft 310. From this sheave the strand 56 passes on to a similar outer sheave 433 mounted on a similar arm 311 on the shaft 34, thence inwardly to an inner sheave 433 mounted on the lower end of the shaft 34, and thence downwardly to receive cover strands 57 drawn from the stationary supplies 37.

In passing over the loop shaped path defined 60 by the two sheaves 333 and the two sheaves 433, the core strand 56 reverses its longitudinal direction of travel while being revolved and so has imposed upon it an axial rotation of twice the speed of revolution of the arms 310 and 311. 65 Hence the strands 57 are wound on the core strand 56.

From the winding point, the covered strand passes down and over an inner sheave 332 analogous to the inner sheave 333 and mounted in 70 the shaft 35. Thence the strand passes radially out to an outer sheave 332 mounted on a second arm 312 on the shaft 35, thence up and over the outer sheave 432 on the second arm 313 of the shaft 34, thence inwardly over the inner sheave

432 in the shaft 34, and thence up and out as before to the take-up device.

In passing over the two sheaves 332 and the two sheaves 432, the rotation of the strand is nullified and the covered strand emerges from the top of the shaft 34 without rotation.

Since in this arrangement there is no such direct physical connection between shafts 34 and 35 as afforded in Fig. 1 by the flier arms 32 and 33, the shaft 34 is now provided with an individual synchronous drive through gears 338 and 344 as shown.

In this embodiment, the various sheaves 332, 333, 432 and 433 may be deeply grooved and mounted to be canted across the path of the strand travelling over them in such a way as to assist in imposing rotation upon the strand or in nullifying the rotation. Thus, in Fig. 16, the strand coming out of the paper at the bottom toward the observer and thence upwardly in the plane of the paper, is frictionally engaged at its right hand side by the outwardly moving leading right hand flange of the sheave 333 and a moment later is frictionally engaged on its left hand side by the inwardly moving trailing left hand flange of the sheave. This frictional couple assists the reversal of path effect in imposing rotation on the strand in the case of the sheaves 333 and 433, and in nullifying the rotation in the case of the sheaves 332 and 432, as also shown in Fig. 17.

In the above descriptions the relative speeds of successive rotating elements have been described for clarity as binary multiples and sub-multiples of each other. They may, however, have any desired and approved speed relationship to each other the chief essential feature common to all the embodiments disclosed being the winding or braiding of cover strands drawn from stationary supplies upon a rotating core 40 strand. A secondary feature characteristic of one species of the invention is the stripping of served cover strands from a rotating core to be reapplied thereto for interbraiding with a second set of cover strands.

It is to be noted that the core 56 is presumed to be torsionally substantially rigid and is not twisted to any appreciable or damaging extent at any point or time in its progress from the core supply reel to the take-up reel. A torsionally yielding core would twist in passing through the flier arm 33 for example and would not rotate at the winding point. Rotation and twist are opposed effects of the flier arm. To the extent that the one appears the other disappears. A torsionally absolutely rigid core would rotate only and not twist at all; a torsionally strengthless core would twist only and not rotate at all.

What is claimed is:

1. The method of braiding on a core which comprises the steps of serving a cover strand on a longitudinally advancing core at one point, stripping the cover strand from the core at another point, and reapplying the stripped cover strand to the core at a third point together with a second cover strand.

2. The method of braiding on a torsionally substantially rigid core which comprises the steps of imposing rotation upon the core strand, applying a cover strand thereto to be wound thereon by the rotation thereof, stripping the cover strand from the core, reapplying the cover strand to the core together with a second cover strand, and annulling the rotation of the covered core.

3. In a braiding machine, a strand guide having means to impose rotation upon a torsionally substantially rigid core passing therethrough by revolving a loop thereof and means to annul the 5 rotation of the core, means to strip a cover strand by revolving a loop thereof from the rotating part of the core, means positioned within the loops to reapply the cover strand to the rotating part of the core, means positioned within the 10 loops to apply a second cover strand to the rotating part of the core, and means to vary the relative directions of application of the two cover strands to the core.

4. In a braiding machine having a stationary 15 strand supply support, a strand switching device comprising a frame associated with the support, flanged and slotted rollers carried by the frame, a rotatable channel trackway coacting with the rollers to confine and drive the same, and means 20 to keep the frame stationary.

5. In a strand handling machine, a frame, a flier rotatably mounted therein, a second flier rotatable within the first flier, a strand supply support within the second flier, and means to 25 drive the two fliers and to hold the support stationary comprising a wobble gear intermeshing with two of said elements.

6. In a strand handling machine, a frame, means to impose rotation upon a strand, a capstan 30 to advance the strand, means to impose rotation upon the capstan as a whole, and means to drive the drum of the capstan comprising a gear rigid upon the frame, and gearing carried by the capstan and meshing on one side with the

side gear and on the other side with a gear upon the drum.

7. A method of serving a cover strand on a torsionally substantially rigid core strand which comprises the steps of passing a torsionally rigid core strand longitudinally of the strand through a looped path whose entrance and exit ends both face in one direction, applying a cover strand to the core strand, passing the combined cover strand and core strand longitudinally through a 10 second looped path whose entrance and exit openings both face in the other direction and revolving the two looped portions of the strands in one common direction of rotation.

8. A method of serving a cover strand on a torsionally substantially rigid core strand which comprises the steps of passing a torsionally rigid core strand longitudinally of the strand through a looped path whose entrance and exit ends both face in one direction, revolving the looped portion 15 of the strand to impose rotation upon the portion of the strand issuing therefrom, applying a cover strand to the rotating part of the core strand to be wound thereon by the rotation thereof, passing the combined cover strand and core strand 20 longitudinally through a second looped path whose entrance and exit openings both face in the other direction, and revolving the second looped portion in the same rotary direction as the first named looped portion to annul the common rotation of the core strand and applied cover 25 strand.

LEO L. WEAVER.
